UNITED STATES PATENT OFFICE.

WILBUR T. CLARK, OF CLEVELAND, OHIO, ASSIGNOR TO THE HANNA FURNACE COMPANY, OF CLEVELAND, OHIO, A CORPORATION OF DELAWARE

CLEANING-DOOR AND CHIMNEY-VALVE.

Specification of Letters Patent.

Patented Nov. 8, 1921.

1,396,676.

Application filed July 21, 1920. Serial No. 397,913.

To all whom it may concern:

Be it known that I, WILBUR T. CLARK, a citizen of the United States of America, residing at Cleveland, in the county of Cuyahoga and State of Ohio, have invented certain new and useful Improvements in Cleaning-Doors and Chimney-Valves, of which the following is a specification.

My invention relates to improvements in combined cleaning door and chimney valve of a type especially designed for use with hot blast stoves, and has for its object the provision of a strong and effective structure of this class which shall be very easily operated by hand and which will comprise a supported valve member that automatically will adjust itself to the valve seat. In addition access is afforded, at all times the valve is closed, for inspection, while the structure readily lends itself to replacement and repair.

Hot blast stoves, in the past, very commonly have utilized independent and more or less cumbersome means for cleaning them and for operating the connections to the chimney stack. These prior means, moreover, have not afforded full and adequate facilities for inspection and ready repair. Again, the valve closure member of such necessarily large size frequently fails to adjust itself accurately to the valve seat unless special means are provided therefor, while the actuation of such massive members requires special mechanism therefor. Accordingly, I have endeavored to meet these practical requirements in a simple and efficient structure for equipping hot blast stoves and the like.

My improvements, as herein embodied and illustrated, may be briefly described as comprising a massive casting adapted to be applied to and form the gas outlet for a hot blast stove. Associated therewith is a removable valve seat, a coacting valve member supported in a traveling shell so that it is capable of independent adjusting movement, and suitable actuating means adapted alternatively to force the valve member strongly against its seat, as by power- actuated gearing, or to close an external opening through which inspection otherwise is afforded upon its rearward engagement by the supporting shell. These members also may be mounted upon a massive hinge support and yoke, whereby repair and

cleaning operations are facilitated. These improvements will be described in detail as preferably embodied for use with a hot blast stove and as illustrated in the accompanying drawings, wherein:

Figure 1 is a vertical sectional view of the combined cleaning door and chimney valve structure.

Fig. 2 is a top view of the same as equipped with actuating gearing for controlling the valve member.

Fig. 3 is a front view of the latter structure, and

Fig. 4 is a fragmentary view in enlarged section on line 4—4 of Fig. 3.

Throughout the several figures of the drawings I have employed the same character of reference to indicate similar parts.

Although the structure of Fig. 1 differs from that of Figs. 2 and 3 in the simpler actuating mechanism, these figures may be referred to generally for an understanding of the common structural features. Thus the massive casting shown in Figs. 1 and 2 is designed for attachment near the base of a hot blast stove to form its gas outlet and afford a frame for the valve structure. Securely bolted to this casting *a* is an annular member *b* forming the valve seat which may readily be removed for refinishing. The two-part casing *c*, *d* likewise is bolted to the frame *a* partially to inclose said valve seat and its coacting valve member *e*, together with the supporting shell *f*. The front opening of this casing is partially closed by the annular shield *g* which is bolted thereto, while the duct *h* to the chimney stack is coupled to the lower portion of the casing, wherein the butterfly valve or damper *i* is positioned.

A heavy supporting yoke *j* is hinged at the right side of the casing whereon there is centrally mounted a hand wheel *k* and a gear wheel *l* for actuating the tapped collar *m* rotatably within its bearing in the yoke. A massive screw member *n* bears terminally against the valve part *e*, extending through a central boss in the supporting shell or carrier *f*, wherein it is held against rotation, to its tapped actuating collar *m*. The valve part or closure *e* is flexibly held in position within its shell by the loose bolts *e'*, while it is supported edgewise upon the bottom flange of the shell in position to be seated against the coacting valve seat.

The shell f , in turn, is supported upon two laterally positioned rollers f' that ride upon the lugs f'' , as shown in the detail, Fig. 4.

5. The annular shield or closure g for the front of the casing is secured to the yoke j , so that when the bolts and clips g', g'' , are removed, the composite device or member e, f , its actuating screw n and said shield g will swing back upon the hinge as soon as said yoke is freed by unscrewing the nuts o' upon the bolts o , which extend to the rear of frame a . This permits the complete opening of the front of the casing, so that 10 the stove may very readily be cleaned out through the gas outlet.

Although a single hand wheel k frequently is sufficient for actuating the valve member e , it is desirable when the structure 20 is of extremely large size to provide a pinion p and secondary hand wheel p' for actuating the gear wheel l . This pinion may be slipped into and out of mesh with said gear wheel l by moving the former longitudinally of its shaft p'' . Thus the extra power obtainable by the gearing is readily availed of for actuating the valve member 25 against its seat whenever necessary.

It will be observed that, as the valve member or closure e is afforded some freedom of movement within its shell f by reason of the loose fit of the bolts e' in the latter, as shown in Fig. 1, said valve member will very readily accommodate itself to the valve 30 seat, against which it may be forced with the multiplied pressure exerted by the screw n and the associated gearing.

Having now described the preferred embodiment of my invention and its principal 40 use and operation, I claim as new and desire to secure by Letters Patent the following:

1. In a structure of the class described, the combination with a substantially vertical 45 valve seat, of a composite co-acting device comprising a supporting shell and an inde-

pendent closure member carried thereby, and actuating mechanism for operating said device, substantially as set forth.

2. In a structure of the class described, 50 the combination with the gas outlet of a stove or the like, of a valve seat therefor, a composite co-acting device comprising a supporting member and an independent closure part adapted to be forced against the valve 55 seat and accommodate itself thereto, and screw-actuated means for operating said composite co-acting device, substantially as set forth.

3. In a structure of the class described, the 60 combination with a frame having a valve seat adapted to be associated with a stove, furnace or the like and afford lateral access thereto, of a carrier, a valve-closure 65 flexibly mounted upon the carrier and thereby adapted to accommodate itself to the valve seat, and actuating means for operating said carrier and valve-closure, substantially as set forth.

4. In a structure of the class described, the 70 combination with a frame having a valve seat adapted to be associated with a stove, furnace or the like and afford lateral communication to the interior thereof, of a carrier, a valve-closure flexibly supported by 75 the carrier in position to accommodate itself to the valve seat, a support whereon said carrier travels, and actuating means for operating said carrier and valve-closure, substantially as set forth. 80

5. In a structure of the class described, the combination with the gas outlet of a stove, furnace or the like, of a valve seat therefor, an associated valve-closure, a carrier therefor, means flexibly supporting the 85 valve-closure upon the carrier, a roller mounting for the carrier, and actuating means for operating said carrier and valve-closure, substantially as set forth.

In testimony whereof I do now affix my 90 signature.

WILBUR T. CLARK,
